Primary Examiner — Keith J Wilson(74) *Attorney, Agent, or Firm* — Che-Yang Chen; Law Office of Michael Chen(57) **CLAIM**

The ornamental design for a sprinkler, as shown and described.

DESCRIPTION

FIG. 1 is a perspective view of sprinkler showing my new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a perspective view showing the sprinkler arranged with a control assembly; and,

FIG. 8 is a perspective view showing the sprinkler arranged with a different type of control assembly.

The broken-lines in the drawings are for illustrative purposes only and forming no part of the claimed design.

1 Claim, 8 Drawing Sheets(56)
